US0D1033393S

(12) **United States Design Patent** (10) **Patent No.:** **US D1,033,393 S**
(45) **Date of Patent:** **** Jul. 2, 2024**

(54) **EARPHONE**

(71) Applicant: **GN Audio A/S**, Ballerup (DK)

(72) Inventor: **Johan Birger**, Ballerup (DK)

(73) Assignee: **GN AUDIO A/S**, Ballerup (DK)

(**) Term: **15 Years**

(21) Appl. No.: **29/826,780**

(22) Filed: **Feb. 15, 2022**

(30) **Foreign Application Priority Data**

Aug. 26, 2021 (WO) WIPO107983

(51) **LOC (14) Cl.** **14-01**

(52) **U.S. Cl.**

(57) **CLAIM**

The ornamental design for an earphone, as shown and described.

DESCRIPTION

FIG. 1 is a Top Side Perspective view of a first embodiment of an earphone showing the new design.

FIG. 2 is a Top Side Perspective view thereof.

FIG. 3 is a Front view thereof.

FIG. 4 is a Rear view thereof.

FIG. 5 is a Left view thereof.

FIG. 6 is a Right view thereof.

FIG. 7 is a Top view thereof.

FIG. 8 is a Bottom view thereof.

FIG. 9 is a Top Side Perspective view thereof.

FIG. 10 is a Top Side Perspective view of a second embodiment of the earphone.

FIG. 11 is a Front view thereof.

FIG. 12 is a Rear view thereof.

FIG. 13 is a Left view thereof.

FIG. 14 is a Right view thereof.

FIG. 15 is a Top view thereof; and,

FIG. 16 is a Bottom view thereof.

The features shown in broken lines depict portions of the earphone that form no part of the claimed design.

1 Claim, 16 Drawing Sheets
